UNITED STATES PATENT OFFICE.

FRANK E. SMALL, OF JAMAICA, NEW YORK.

KITCHEN FORK.

Application filed December 16, 1920. Serial No. 431,156.

To all whom it may concern:

Be it known that I, FRANK E. SMALL, citizen of the United States of America, and resident of Jamaica, Long Island, in the county of Queens and State of New York, have invented new and useful Improvements in Kitchen Forks, of which the following is a specification.

This invention relates to forks and more particularly to a fork for kitchen or culinary purposes and providing means whereby vegetables or other articles of food impaled upon the tines of the fork may readily be ejected therefrom.

While various attempts have heretofore been made to provide forks with ejecting devices, so far as is known, no entirely satisfactory device of this kind has as yet come into general use. In many cases the proposed ejector devices have been so complicated and expensive to make, as well as so cumbersome and heavy, as to preclude their employment to any considerable extent for the purpose for which they are designed.

One object of the present invention is to provide a fork with an ejector device of light weight and of simple and inexpensive construction, and which at the same time shall be well adapted for its intended use.

As it is quite desirable to guide the ejector member proper by engagement with the fork tines, it is clearly evident that the freedom of movement of such ejector member depends to a large extent upon the degree to which those tines with which it engages approach substantial parallelism, and that the bending of one or more of such tines may render the device entirely inoperative.

Such bending of fork tines, particularly the outside tines, where three or more are employed, is of frequent occurrence in culinary use, and a further object of this invention is to so design an ejector device that its freedom of movement will be but little impaired by any ordinary bending of the tines of the fork. To this end it is proposed to form the ejector as a substantially flat plate having a single guide opening therein for engagement with one tine only of the fork. When

a three tine fork is employed, this opening may engage the central tine, but if a fork having a different number of tines be employed, the opening in the ejector plate may be arranged to engage such tine as is found to be most convenient in practice. In any event, it is contemplated that the ejector

plate will be substantially free from contact with any of the other tines but may if desired extend sufficiently close thereto to insure the ejection of material of substantial size impaled thereon.

In many cases, when the provision of an ejector device has been attempted, it has been found necessary to provide a special form of fork, or to make openings in or secure permanent attachments to forks of existing types in order to permit of the proper location of the ejector device. Furthermore with the usual arrangements, it is not easy, if possible, to remove the ejector device from the fork, and in many cases this occasions difficulty in cleaning of the fork with its appurtenance, resulting in an unsanitary condition rendering it undesirable as an implement for use in the preparation of articles of food. A further object of the present invention is to provide an ejector device capable of application to an ordinary type of commercial fork such as is employed for kitchen and culinary use and at the same time to so devise such ejector that it may readily and quickly be removed for cleaning and as easily restored to operative position.

To this end, and as herein disclosed, the ejector device when applied to a three tine, loop-handled wire fork, may comprise an ejector plate as aforesaid having an opening slidably engaging the central tine of the fork, an actuating member having guide notches into engagement with which the spaced bars of the fork handle may be sprung, and suitable means for connecting the ejector plate and actuating member.

While the device has been illustrated as applied to a specific type of fork, it is clearly evident that it might be adapted by slight modifications in shape or relative proportion of parts for application to other known forms of fork, and although the ejector proper has been illustrated as comprising a substantially flat plate it is contemplated that ejector elements of other and equivalent forms might well be substituted for that herein specifically shown.

A preferred form of device is illustrated in the accompanying drawings in which—

Fig. 1 is a plan view of the fork illustrating the same in position for use with the ejector member in inoperative position.

Fig. 2 is a side elevation of the fork with the parts arranged as in Fig. 1.

Fig. 3 is a fragmentary view of the left-hand portion of the device shown in Fig. 1, but indicating the ejector device as having been moved to eject material impaled on the tines of the fork.

Fig. 4 is a cross section of the device on the line *a*—*b* of Fig. 2.

Fig. 5, is a cross section on the line *c*—*d*, of Fig. 2; and

10 Fig. 6 is a side elevation of the ejector device removed from the fork.

As herein illustrated, the fork comprises three tines 1, 2, 3, respectively, which may be formed of wire if desired and which are 15 herein indicated as twisted together at 4. The handle of the fork comprises a loop-like open frame consisting of the side bars 5, 6, arranged substantially parallel and spaced apart one from the other, such bars 20 being integrally united if desired to form the closed end 7, and may be twisted at 4 with the tine members of the fork. If desired, two of the tine members and the handle member may be formed of a continuous 25 piece of wire intertwined at 4 with a second piece forming the third tine member. The exact mode of construction of the fork however, is immaterial in so far as the fundamental features of the present invention 30 are concerned.

8 is an ejector member and 9 is an actuator thereof, said members being suitably connected by means of a substantially rigid rod or wire 10. The members 8 and 9 may 35 be secured to the ends of the rod 10 in any suitable manner, as by soldering or brazing. It is contemplated however, as within the scope of the invention, that the members 8 and 9 might be formed integral with the 40 bar or wire 10, as for example by casting the same as a unitary structure, or by forming the members 8 and 9 by suitably twisting and bending the piece of wire forming the rod 10.

45 Regardless of the mode of manufacture of the ejector device it is preferred to form the plate 8 substantially as indicated in Fig. 4, wherein the ejector proper is shown as comprising a relatively thin plate of substantially elliptical form. This plate is provided 50 adjacent its center with an opening 11, whereby the plate may be guided for free sliding movement along the member 2.

The plate is preferably so arranged that 55 its major axis lies substantially in the plane of the tines of the fork, but is of such dimension that while substantially filling the spaces between the central tine and the outer tines, it does not actually engage the 60 outer tines. The actuator member 9 is also of substantially elliptical form and is provided with open ended notches 12, 13, at the ends of its major axis. These notches 65 are arranged for slidable engagement with the bars 5 and 6 respectively of the handle.

In assembling the fork and ejector device, it is merely necessary to slip the plate 8 over the central tine 2 and move the same backward until the actuator plate 9 occupies a position adjacent the center of length 70 of the handle. When in this position the bars 5, 6, may readily be sprung apart sufficiently to permit the plate 9 to be snapped between the same whereby to permit the bars 5, 6, to loosely engage within the 75 notches 12, 13. When thus arranged, the device is ready for use, and as indicated in Fig. 1 the ejector plate 8 may be retracted by the thumb or finger of the user, thus permitting an article of food, as for example a 80 potato, indicated at *A* in the drawing, to be impaled on the tines of the fork. For removing such article from the fork tines, the operator by pushing upon the actuator plate 9 may cause the ejector plate 8 to 85 slide along the tine 2 until it occupies a position such as shown in Fig. 3, in which position the potato or other article of food will be discharged from the fork tines.

For cleaning the fork the ejector device 90 may be removed therefrom by springing apart the bars 5, 6, of the fork handle.

Having thus described the invention in a preferred embodiment thereof together with the mode of use of the same, what I claim 95 and desire to secure by Letters Patent of the United States is:

1. A detachable ejector device for use with kitchen forks having three tines, comprising an ejector plate having an opening for receiving the central tine of the fork, said plate extending on opposite sides of said opening substantially across the space between the central tine and the outer tines but without engaging the latter, and a finger 105 engageable member for sliding said plate along said central tine.

2. A detachable ejector device for use with a fork having a plurality of tines, said device comprising an ejector member having 110 sliding engagement with one of said tines only and extending to points adjacent the other tine or tines but without contacting with the latter.

3. A detachable ejector device for use with a fork having a handle comprising substantially parallel spaced members, said device comprising an ejector member slidably associated with the fork tines, an actuating member having oppositely outwardly directed open notches slidably engageable with the respective spaced members of the handle and means for connecting said ejector member and said actuating member.

4. In a detachable ejector device for use 125 with wire handled forks having handles comprising spaced substantially parallel bars, an ejector member slidably engageable with a fork tine, an actuator therefor comprising a substantially elliptical plate hav- 130

ing notches at the opposite ends of its major axis for engagement with the respective bars of the handle and a rod having its opposite ends secured to said ejector and actuator re-

25 constructed and arranged to be slidably engaged with the respective parallel bars by springing the latter apart and into engagement with said notches.

5 5. A detachable ejector device for use with

a fork provided with a relatively straight handle having parallelly spaced elements

wire handled forks having handles comprising substantially parallel spaced members, said device comprising an ejector plate hav-

30 ing an opening for receiving one of the fork tines, an actuator member constructed and

10 arranged for insertion between said parallel members of the handle by springing the latter apart, and a rigid rod connecting said

35 plate and actuator member.

6. In combination with an ejector member arranged for association with the tines of a fork having a handle comprising a pair of substantially parallel spaced bars, an ac-

40 tuator plate of substantially elliptical form

20 having open ended notches at the opposite ends of one of its axes, said notches being

transmitting movement from said actuator to said ejector member, said actuator and ejector members being constructed and arranged for ready application to or removal from the fork.

Signed by me at Jamaica, New York this

14th day of December, 1920.

FRANK E. SMALL.
